FIG.1

FIG.2

FIG.3

FIG.4

FIG. 1 is a side elevation of the binoculars;
FIG. 2 is a view as seen from the top thereof as illustrated in FIG. 1;

FIG. 3 is a view as seen from the bottom thereof as illustrated in FIG. 1; and

FIG. 4 is a side elevation as seen from the opposite side to that illustrated in FIG. 1.

The characteristic feature of my design resides in the central casing portion of the binoculars.

This application is a continuation-in-part of my application, Serial No. D. 72,697 filed December 3, 1962.

I claim:
The ornamental design for binoculars, as shown and described.
